UNITED STATES PATENT OFFICE

EDWIN LUNDGREN, OF FREDERICK, MARYLAND, ASSIGNOR TO INTERNATIONAL COMBUSTION ENGINEERING CORPORATION, OF NEW YORK, N. Y., A CORPORATION OF DELAWARE

FURNACE WALL STRUCTURE

Application filed December 12, 1928. Serial No. 325,553.

Multiple retort underfeed stokers are commonly provided with relatively deep ash pockets having clinker grinders at the bottoms thereof for effecting the gradual discharge of ashes. In stokers of this type, the hot ashes entering the deep ash pocket and the burning of unconsumed particles of fuel therein, subject the front wall of the ash pocket to an intense heat, and it has been found that the front wall structures at present in general commercial use, are not only incapable of effectively withstanding such intense heat but, also, in case portions thereof are burned out or otherwise injured it is difficult to repair or replace them.

One of the objects of the present invention is to provide a front wall structure for the ash pocket of a stoker of the type above indicated in which said disadvantages of the prior constructions are overcome.

Another object of the invention is to provide a furnace wall structure in which the component parts thereof, while permitted to expand and contract freely and are securely held in place, may be easily removed for replacement or repair.

Still another object of the invention is to provide novel and improved means for detachably securing the component parts of a furnace wall structure in place.

These and other objects of the invention and features whereby they may be attained, will be clearly understood from the following description and accompanying drawings, in which:

Figure 1 is a longitudinal sectional view, partly diagrammatical and partly in elevation, of the rear portion of an underfeed stoker embodying the features of the invention in their preferred form;

Fig. 2 is a sectional elevation, on a reduced scale and partly diagrammatical, taken on the line 2—2 of Fig. 1;

Fig. 3 is a sectional elevation, on an enlarged scale, corresponding to a portion of Fig. 1; and

Fig. 4 is a detail sectional plan view taken substantially on the line 4—4 of Fig. 3.

The multiple retort underfeed stoker illustrated in the drawings, is provided with a re-

tort section 2, a relatively deep ash pocket 4 at the rear thereof, and clinker grinders 6 at the bottom of the ash pocket. The ash pocket is provided with a front wall 8, side walls 10 and a rear wall 12, the rear well being lined with boiler tubes 14. A supporting wall 16 for the rear ends of the retorts is made up of I-beams and is spaced a distance in front of the front wall 8 of the ash pocket. This wall 16 is provided with an opening 18 through which air may pass from the wind box to the space between said wall and the front wall of the ash pocket, the supply of air to this space being controlled separately from the supply of air to the retort section by means including a damper 20.

In accordance with my invention, the front wall 8 of the ash pocket is made up of bricks or blocks 22 of suitable refractory material that are arranged in superposed horizontal rows with the blocks of adjacent rows arranged in staggered relation. The several blocks which make up the front wall are supported on a flanged seat or shelf 24 secured on a horizontal I-beam 26. The space between the top of this wall structure and the rear ends of the retorts is closed by bars or keys 28 having their rear ends resting upon the top of the structure and their forward portions loosely mounted in a bracket 30 projecting from a suitable supporting beam 31 at the rear of the retort walls, the mounting of the bars or keys 28 being such as to permit them to raise and lower during the expansion and contraction of the front wall. The blocks at the upper portion of the front wall are provided with perforations 32 for directing air into the ash pocket to assist in the combustion of any unconsumed fuel therein, the other blocks being preferably unperforated.

The adjacent sides of adjacent blocks are provided with tongue and groove connections 36 to assist in maintaining the blocks in proper relation.

Each block has a body portion having flat rear, top and bottom sides or faces. The front side of the block is recessed to provide a centrally located vertical web or rib 38. This rib 38 on each block is provided with an

- elongated vertical slot 40 extending transversely therethrough. The slotted rib 38 serves as a means for attaching each block to an anchoring rod 42. This rod has a U-shaped bend in one end to provide an intermediate or transverse leg 44 and an end leg 46 which is turned upwardly with relation to the body of the rod as shown. The other end of the rod is bent downwardly and is adapted to be received in an aperture in an angle iron bracket 48 secured to the supporting wall 16, there being a bracket opposite each row of blocks and extending between the side walls of the furnace.
- To secure each block in place by means of its anchoring rod 42, the rod is turned upwardly, as shown in dotted lines in Fig. 3 so as to place the end leg 46 in upright position, whereupon the U-shaped bent end of the rod is passed through the vertical slot 40 in the block and then the rod is swung downwardly and its bent outer end is inserted in the aperture in the associated angle iron 48. When an anchoring rod is thus attached, the leg 46 of the rod prevents disengagement of the rod from the block. Each anchoring rod 42 securely holds its block from appreciable fore and aft movement, but the block is free to move vertically and laterally to allow for expansion and contraction of the wall. When it is desired to remove a block for replacement or repair, the outer or forward end of the anchoring rod 42 is disengaged from its bracket 48 and the rod swung upwardly so as to permit it to be removed from the block.
- It will be apparent that in my improved wall structure as above described, the several blocks are securely held, and may be easily removed and replaced; and the structure as a whole may freely expand and contract, and is capable of effectively withstanding the intense heat to which it may be subjected when employed as the front wall of the ash pocket of a stocker of the type above indicated.
- As will be evident to those skilled in the art, my invention permits various modifications without departing from the spirit thereof or the scope of the appended claims.
- What I claim is:
1. In a multiple retort underfeed furnace having a relatively deep ash pocket with a clinker grinder arranged at the bottom thereof, the improvement which consists in the front wall of the ash pocket being made up of blocks of refractory material arranged in superposed rows with the blocks of adjacent rows arranged in staggered relation, a metal wall structure spaced a distance in front of said front wall, and connections between said structure and said front wall for holding each block from fore and aft movement but permitting vertical and lateral movements thereof to allow for expansion and contraction of said wall.

2. A furnace wall structure made of blocks of refractory material, and a device detachably secured at a point remote from each block for detachably securing the block in place in such a manner as to permit expansion and contraction of said structure, each of said devices incapable of being detached from the associated block without first detaching it from said support. 70

3. A furnace wall structure comprising blocks of refractory material, and means for holding each block from movement transversely of the structure but permitting vertical and lateral movements thereof to allow for expansion and contraction of said structure, comprising a support spaced a distance from one side of the blocks, and a member having its ends respectively detachably secured to said support and each block, each of said members being incapable of being detached from its block without first detaching it from said support. 75

4. A furnace wall structure comprising blocks of refractory material, and means for holding each block from movement transversely of the structure but permitting vertical and lateral movements thereof to allow for expansion and contraction of said structure, comprising a support spaced a distance from one side of the blocks, and a member having one end detachably secured to said support and its other end in detachable interlocking engagement with said block whereby upon disengaging said member from said support the member may be moved to disengage its end from the block, each of said members being incapable of being detached from its block without first detaching it from said support. 80

5. A furnace wall structure comprising blocks, each block having a projecting centrally located vertical rib having an elongated vertical slot extending transversely therethrough, a support spaced a distance from one side of the blocks, and means for holding each block from movement toward and from said support but permitting lateral and vertical movements thereof to allow for expansion and contraction, comprising a rod having a U-shaped bend in one end with the end leg thereof bent at an angle to the body of said rod and adapted to be passed through said slot, so that when the rod is swung down into substantially horizontal position said bent end is caused to interlock with said rib, the other end of said rod being adapted to be detachably secured to said support. 85

6. In a multiple retort underfeed stoker having a relatively deep ash pocket with a clinker grinder arranged at the bottom thereof, the improvement which consists in the front wall of the ash pocket being made up of blocks of refractory material arranged in superposed rows with the blocks of adjacent rows arranged in staggered relation, a metal wall structure spaced a distance in front of said front wall, and connections between said structure and said front wall for holding each block from fore and aft movement but permitting vertical and lateral movements thereof to allow for expansion and contraction of said wall. 90

wall structure spaced a distance in front of said front wall, connections between said structure and said front wall for holding each block from fore and aft movement but permitting vertical and lateral movements there-
5 of to allow for expansion and contraction of said front wall, a shelf member on which said blocks rest, and fuel supporting keys having their rear portions resting upon the top row of blocks and capable of vertical movement to allow for vertical expansion and contraction of the blocks.
10

In testimony whereof, I have signed my name to this specification this 7th day of December, 1928.

15 EDWIN LUNDGREN.
